[57] CLAIM

The ornamental design for the ribbed sleeve for lock, as shown and described.

DESCRIPTION

FIG. 1 is a top perspective view of the ribbed sleeve for lock of the present invention affixed to a padlock;

FIG. 2 is a bottom perspective view of the ribbed sleeve for lock of FIG. 1;

FIG. 3 is a front elevation view of the ribbed sleeve for lock of FIG. 1; the rear elevation view is a mirror image;

FIG. 4 is a left side elevation view of the ribbed sleeve for lock of FIG. 1; the right side elevation view is a mirror image;

FIG. 5 is a top plan view of the ribbed sleeve for lock of FIG. 1; and,

FIG. 6 is a bottom plan view of the ribbed sleeve for lock of FIG. 1.

The phantom line disclosures of the shackles, key cylinder, and shackle holes are shown for illustrative purposes only and form no part of the claimed design.
